BETHEL ABIEL REVELLI, OF TURIN, ITALY, ASSIGNOR, BY MESNE ASSIGNMENTS, TO METALLURGICA BRESCIANA GIA TEMPINI, OF FIUMEGRANDE, BRESCIA, ITALY, A COMPANY OF ITALY

AUTOMATIC FIREARM ACTUATED BY COMPRESSED AIR

Application filed August 21, 1929, Serial No. 387,431, and in Italy June 6, 1929.

The present invention has for its object an automatic fire-arm actuated by compressed air and has for its aim to simplify the construction while obtaining a regular action and a very much reduced recoil, in 5 addition to a firing speed which can be reduced at will down to a few rounds per minute.

The fundamental idea on which the present invention is based consists in that the breech is caused to act as a compression cylinder, and the obturator which is movable directly in the said breech acts as a piston compressor, discharge valve and admission 15 valve for air thus allowing different pressures to be obtained during the phases of the automatic cycle of action.

In this device several members are dispensed with, that is to say special closing 20 devices, spring shock absorbers retarding means and the like, the same results being obtained as with the said special members but in a better and more economical way.

The accompanying drawing shows diagrammatically by way of example, a few forms of construction of the fire-arm according 25 to the present invention.

Figure 1 is a diagrammatic part section of the fire-arm according to the invention.

Figure 2 shows the detail thereof.

Figures 3 and 4 are diagrams of the pressure in the breech chamber during the course respectively of the recoil and return of the obturator.

Figure 5 is a diagrammatic part axial section of the fire-arm provided with devices for regulating the pressure according to the present invention.

Figure 6 is a diagrammatic part section 40 analogous to Figure 5 of another form of construction.

Figure 7 is a diagrammatic axial section of a third form of construction.

With reference to Figure 1, the fire-arm 45 is constituted by a breech chamber 1 to

which is fixed the barrel 2; in the interior of the chamber 1 slides the obturating piston 3 consisting of a cylinder of relatively large diameter, with the object of compressing a large volume of air, and of a considerable weight, with the object of retarding by its inertia, the opening of the explosion chamber.

The part of the breech chamber corresponding to the travel of the piston has no 55 opening through which air can escape and is closed at the rear by a screw cap 4. In order to secure hermetic sealing, the piston may be provided with one or more piston rings 5 of the type used in pistons of 60 internal combustion engines.

Between the piston 3 and the cap 4 is arranged the recuperating spring 6. The percussion means consists of a small lever 7 (see Figure 2) which strikes the cap of 65 the cartridge when on the piston reaching its closing position the external arm of the lever strikes against a projection 8 of the breech chamber.

The fire-arm as it has been described with 70 reference to Fig. 1 would not work well for the air compressed by the piston in its recoil would produce an acceleration of the return travel, that is to say, it would have the same effect as a strong recuperating 75 spring giving rise to an excessive firing speed and to a too violent blow of the piston against the barrel in its return.

It is consequently necessary to regulate 80 the pressure of the air so that at the end of the recoil the compressed air can find a discharge. In this manner the return travel commences without too much force. On the other hand during the said return travel 85 every opening must be closed again so that the reduction in pressure produced by the movement of the piston produces a certain braking of this latter. Finally, it is necessary that during the latter part of the return travel any braking action is removed 90

in order to allow the piston to strike against the cartridge with the force necessary for firing.

This can be obtained by the cycle represented in Figures 3 and 4, and can be effected in practice by providing the fire-arm described above in principle with systems of valves of which Figures 5, 6 and 7 give a few examples.

10 In the form of construction shown in Figure 5 the valve is constituted by a rod 9 connected to the piston 3 and passing through a hole in the cap 4 and provided with a stuffing box 10. The rod presents 15 two series of longitudinal discharge grooves 11 and 12, which allow the air to pass when they are within the hole in the cap.

The fire-arm then acts as follows:

At the instant of firing, after the retardation due to the inertia, the piston commences its recoil (point A of the diagram Figure 3). The discharge port 11 is in the opening position during the part AB of the curve (Figure 3), that is to say the 25 air can pass out freely and the pressure remains normal. When the cylindrical portion of the rod 9 commences to slide in the cap the compression chamber is closed and the air is compressed, thus absorbing 30 the recoil of the piston.

When the piston has arrived at the point corresponding to C (Figure 3) the air can again be discharged through the port 12 and the normal pressure is re-established. During 35 the return travel the action will be the reverse of that above described. During the travel DC of the diagram (Figure 4) the valve is open and the pressure is normal; during the travel corresponding to CB the 40 valve is closed and there is a progressive reduction in pressure and the travel of the piston is retarded. Through-out the distance corresponding to BA the valve is open, air is admitted, and the piston is accelerated so 45 that it can strike the cap of the cartridge with the necessary force.

An improvement in the said system is effected by a supplementary discharge which remains open throughout the whole cycle 50 and has for its effect to lower throughout the whole diagram the curves of compression and depression thus producing an action analogous to that described above but having a different firing speed.

55 This supplementary discharge is realized in practice by opening a window in the wall of the breech or of the cap and providing it with a regulatable closing means. Thus different firing speeds may be obtained.

60 According to means provided for closing the said supplementary discharge there could be two, three, four, or more firing speeds, or even a continuous variation of speed.

65 Figure 6 represents another form of con-

struction in which in order to dispense with the rod 9 shown in figure 5, a fixed opening 13 is made in the breech chamber and a valve 14 is provided in the cap 4.

The opening 13 remains open during a 70 certain part of the travel of the piston 3 and is subsequently closed by the piston itself during the remaining portion of the travel. On the other hand, the valve 14 only opens when it is struck by the piston at 75 the end of the recoil and is closed again when the piston commences its return travel.

Finally, Figure 7 represents another form in which piston rings 5 are provided at the two ends of the piston and in which any 80 form of valve is replaced by fixed openings.

The piston 3 has a longitudinal passage 15 open at the end and a window of elongated form 16, and in the wall of the breech case 1 a fixed port 17 is provided. This form of 85 construction gives the same diagram as is shown in Figures 3 and 4. The opening 17 allows air to pass during the first part of the recoil travel until it is closed by the body of the piston 3 itself. Thus the period of 90 compression ceases when the window 16 is opposite the opening 17 of the breech chamber.

In the return the second cycle will be produced according to the diagram of 95 Figure 4.

It is obvious that the form and details of construction could be varied as desired without departing from the scope of the present invention.

100 What I claim is:

1. In an automatic fire-arm, a barrel, a breech, a compression chamber in said breech, a movable member acting as obturating piston for said barrel and air compressing piston for said compression chamber, an opening being provided in the wall of said chamber in proximity to the rear end of said piston when it is in its foremost position in such a way as to be closed by said piston 105 when it has effected a predetermined initial part of its recoil travel and a valve arranged in the rear end of said compression chamber, said valve being opened by the piston before this latter reaches the end of its recoil travel. 110

2. In an automatic firearm, in combination with a barrel, a breech, and an air compression chamber in said breech, of a movable member acting as breech bolt for said barrel and as a piston for said compression chamber; and means for creating in said chamber during an intermediate part of the piston movement an increasing pressure during the rearward movement and an increasing partial vacuum during the forward 115 movement of said movable member and to remove said pressure and said partial vacuum during the final parts of the movement of said movable member.

3. In an automatic firearm, in combination 120

with a barrel, a breech, and an air compression chamber in said breech, of a movable member acting as breech bolt for said barrel and as a piston for said compression chamber, and means for placing said compression chamber in connection with the exterior before said movable member has reached the end of its rearward and forward movement respectively.

10 In testimony that I claim the foregoing as my invention, I have signed my name.

BETHEL ABIEL REVELLI.
